ARTICLE OF REPOSE FOR SUPPORTING
THE BODY OF A PERSON

Anton Lorenz, Buffalo, N. Y.

Application November 19, 1949, Serial No. 128,285

4 Claims. (Cl. 155—106)

1

This invention relates to articles of furniture and more particularly to reclining articles of furniture, wherein the seat and the back-rest may be moved through the medium of a link-system from a sitting position into a reclined position and vice versa.

An object of the present invention is to provide a reclining article of furniture of above described type wherein during a displacement of the connected back-rest and seat from one position into another one the back-rest and the seat are moved through different angles.

Another object of the present invention is to provide a bed with a bed-bottom, the sections of which are adjustable relative to each other and may be readily brought from one position into another one by a person resting on the bed.

A further object of the present invention is to improve on the art of reclining articles of furniture as now ordinarily made.

Other objects and structural details of the invention will be apparent from the following description when read in conjunction with the accompanying drawing forming part of this specification wherein:

Fig. 1 is a side elevational view of a reclining chair according to the invention, a portion of a side of the support being broken away,

Fig. 2 is a side elevational view of a chaise longue according to the invention, a portion of a side of the supporting frame being broken away,

Fig. 3 is a side elevational view of a different embodiment of a chaise longue according to the invention, a portion of a side of the supporting frame being broken away,

Fig. 4 is a top plan view of a bed according to the invention,

Fig. 5 is a side elevational view of the bed shown in Fig. 4, and

Fig. 6 is a side elevational view of the bed similar to that shown in Fig. 5 wherein, however, the sections of the articulated bed-bottom are in an angular position relative to each other.

Referring now to Fig. 1, 20 generally indicates a support comprising side frames 22 and 24 rigidly connected with each other by cross-bars 26 and 28.

A back-supporting member or back-rest 30 is swingably mounted on the support 20 at 32. On each side of the chair said back-rest 30 has an extension 33 projecting beyond the pivotal connection 32 between the back-rest 30 and the support 20. Said extension 33 is integral with the back-rest 30.

The rear end portion of a rockable seat 34 is

2

swingably mounted on said support 20 at 36. The pivotal connection 36 between the seat 34 and the support 20 is spaced from the pivotal connection 32 between the back-rest 30 and the support 20.

5 An extension 33 rigidly connected with the seat 34 projects backwardly beyond the pivotal connection 36 between the seat 34 and the support 20 and beyond the pivotal connection 32 between the back-rest 30 and the support 20. Said extension 33 passes through an aperture of the back-rest 30.

10 On each side of the chair a connecting link 40 is pivotally connected with the extension 33 of the seat 34 at 42 and with the extension 33 of the back-rest 30 at 44.

On each side of the chair an arm-rest 46 is rigidly connected with the back-rest 30.

15 As will be readily understood, the extension 33 of the back-rest 30, the connecting link 40 and the extension 33 of the seat 34 constitute the movable links of a four-sided link-system, while the portion of the support 20 between the pivots 32 and 36 constitutes the stationary link of said four-sided link-system.

20 The cross-bar 28 between the side frames 22 and 24 of the support 20 acts as a stop for limiting the sitting position of the seat 34 and the movable members of the chair connected therewith, as shown in full lines in Fig. 1. When the back-rest 30 is swung about its pivot 32 into the extreme reclined position shown in dash-and-dot lines in Fig. 1, the seat 34 connected with said back-rest 30 in the manner described above is

25 swung about its pivot 36 into the reclined position shown in dash-and-dot lines. During such a displacement of the back-rest and seat from the sitting position into the reclined position, the angle between the seat and the back-rest is increased. The extreme reclined position of the movable members of the chair, as shown in dash-and-dot lines, is limited by an abutment of the extension 33 of the back-rest 30 against a stop 48 adjustably mounted in a slot 50 of the support 20.

30 The stop 48 may be held in its adjusted position by means of a screw (not shown). According to the embodiment shown in Fig. 2, again the back-rest 130 and the seat 134 are pivoted to the supporting frame 120 of the chaise longue at the points 132 and 136 spaced from each other. The downward extension 133 of the back-rest 130, the rearward extension 133 of the seat 134 and the connecting link 140 are provided with a series of bores 152. The pin 142

35 may be selectively engaged with two bores of the

series of bores 152 of the extension 138 and of the connecting link 140; the pin 144 may be selectively engaged with two bores of the series of bores 152 of the extension 133 and of the connecting link 140. Thus the effective length of the extension 138, of the connecting link 140, and/or of the extension 133 may be readily adjusted.

The leg-supporting member or leg-rest 154 arranged at an angle to the seat 134 is rigidly connected with the latter.

A cross-bar 156 connecting the side frames 122 and 124 of the support 120 with each other is arranged in a gap between the rear end portion of the seat 134 and the back-rest 130.

The sitting position of the movable members of the chaise longue shown in full lines is limited by a cross-bar 128 arranged for abutting engagement with the seat 134, the extreme reclined position of the movable members of the chair shown in dash-and-dot lines is limited by an abutment of the back-rest against a stop 148 carried by the support 120.

According to the embodiment of a chaise longue shown in Fig. 3, the back-rest 230 is pivoted to the support 220 at 232. The rear end portion of the seat 234 is pivoted to the support 220 at 236 at a point spaced from the pivotal connection 232 between the back-rest and the support. Again the rearward extension 238 of the seat 234 and the downward extension 238 of the back-rest 230 are provided with a series of bores 252. The pivot 242 connecting the upper end of the connecting link 240 with the extension 238 of the seat 234 may be inserted into one or the other of the set of bores 252 of the extension 238. The pivot 244 connecting the lower end of the connecting link 240 with the extension 238 of the back-rest 230 may be inserted into one or the other of the set of bores 252 of the extension 238.

The leg-rest 254 is swingably mounted on the front end portion of the seat 234 at 260. The movements of the leg-rest 254 are controlled by a controlling mechanism which in the embodiment shown in Fig. 3 is in the shape of a controlling link 262. One end of said controlling link 262 is pivoted to the leg-rest 254 at 264, the other end of said controlling link 262 is pivoted to the support 220 at 266.

The sitting position of the movable members of the chaise longue shown in full lines is limited by a cross-bar 226 of the support 220 arranged for abutting engagement with the seat 234.

The arm-rests 246 of the chaise longue constitute an integral portion of the frame thereof of tubular material. The arm-rests 246 are connected with each other by the portion 249 of the frame, which also constitutes a stop for abutting cooperation with the back-rest 230 so as to limit the extreme reclined position of the movable members of the chaise longue shown in dash-and-dot lines.

During the movement of the connected back-rest 230 and seat 234 from the sitting position into the reclined position, the leg-rest 254 is brought into the dash-and-dot line position through the medium of the controlling link 262.

According to the embodiment shown in Figs. 4-6 the support 320 of the bed comprises the head-end 268, the foot-end 370 and the pair of longitudinal rails 372. Said parts of the support 320 are rigidly connected with each other in any suitable manner.

The back-supporting member or head-section 330 of the bed-bottom is swingably mounted at

332 on lugs 374 carried by the longitudinal rails 372 of the support 320. On each side of the bed an extension 333 is rigidly connected with the head-section 330.

The end of the rockable seat-portion 334 of the bed-bottom adjacent to said head-section 330 is swingably mounted on the lugs 374 carried by the longitudinal rails 372 at 336 at a point spaced from the pivotal connection 332 between said head-section 330 and said lugs 374. On each side of the bed an extension 338 is rigidly connected with said seat-portion 334. Said extension 338 projects beyond the pivotal connection 336 between the rockable seat-portion 334 and the support 320 and beyond the pivotal connection 332 between the head-section 330 and the support 320. Said extension 338 is provided with a series of bores 352.

On each side of the bed one end of a connecting link 340 of telescopic construction is pivoted to the extension 333 of the head-section 330 at 344. The pivot 344 may be disengageable, if so desired. A pin 342 may be selectively engaged with one bore of the series of bores 352 of the extension 338 of the seat-portion 334. If the set screw 341 of the telescopic connecting link 340 is loosened or if either the pivot 342 or the pivot 344 is disengaged, the head-section 330 and the rockable seat-portion 334 may be brought into alignment with each other as shown in Figs. 4 and 5. Then the head-section 330 rests on the lugs 336 carried by the longitudinal rails 372 of the support 320 and the seat-portion 334 rests on the lugs 378 likewise carried by the longitudinal rails 372 of the support 320.

The leg-supporting member or foot-section 354 of the articulated bed-bottom is pivotally connected with the rockable seat-portion 334 at 360. On each side of the bed said foot-section is provided with a lug 376 carrying a pin 364 slidably and rotatably engaged with a longitudinal slot 361 arranged at one end of a controlling link 362. The other end of each controlling link 362 is pivotally connected with the lug 378 of the support 320 at 366. Furthermore, on each side of the bed the foot-section 354 is provided at its free end with a lug 388 carrying a roller 390. When the foot-section 354 is in a substantially horizontal position as shown in Fig. 5, said rollers 390 are in engagement with the longitudinal rails 372 of the support 320.

When the members of the bed are in the position shown in full lines in Figs. 4 and 5, a person may rest on a perfectly flat surface.

If a person wishes to rest on the bed in a reclined position with the legs elevated, the following steps may be taken: For example, assuming the set screw 341 of the telescopic connecting link 340 is loose and the pivots 342 and 344 are engaged as shown in Fig. 5, at first the head-section 330 is brought into the upright position 330', whereupon the set screw is tightened so as to fix the effective length of the connecting link. Thereupon the head-section 330 may be swung about its pivot 332 in counter-clockwise direction. During the movement of the head-section from the position 330' shown in Fig. 5 into the position shown in full lines in Fig. 6 the rollers 390 of the foot-section 354 roll along the longitudinal rails 372, the pivot 364 mounted on the lug 376 of the foot-section 354 sliding along the slot 361 of the controlling link 362 causes a slight upward swinging of said controlling link 362 about its pivot 366. When the members of the bed are in the position shown in full lines in Fig. 6 the pivot 364 mounted on the lug 376 of

the foot-section 354 is in engagement with the left hand end of the slot 361. Now, when the counter-clockwise swinging movement of the head-section 330 is continued and said head-section is brought into the position 330'', for example, shown in dash-and-dot lines in Fig. 6, the controlling link 362 now in pivotal connection with the foot-section 354 controls the further movements of said foot-section which reaches the position 354''. Of course, during above-described movement, the stationary portion 374 of the seat-section, rigid with the support 320, remains in its position.

If a different relative position between the head-section and the seat-section is desired in the reclined position, the pivot 342 of the connecting link 340 may be engaged with another bore of the series of bores 352.

Furthermore, a modification in the relative position of the members of the bed may be obtained by swinging the head-section at first into the position 330'' shown in Fig. 5 and setting the effective length of the connecting link 340 for a greater length, as may be seen in said Fig. 5. On the other hand, of course, the head-section 330 may be used in said position 330''' as a support for the back of a person who wishes to sit up in the bed without having the legs in an elevated position.

The aligned position of the sections 330, 334 and 354 of the bed-bottom may be readily re-established by loosening the set screw 341 of the telescopic connecting link 340 or else by disengaging either one of the pivots 342 or 344.

Although not shown in the drawings, it is understood that every embodiment of a reclining article of furniture may be equipped with a locking device by means of which the movable members of the article may be held in any desired position.

I have described preferred embodiments of my invention, but it is understood, that this disclosure is for the purpose of illustration and that various omissions or changes in shape, proportion and arrangement of parts, as well as the substitution of equivalent elements for those, herein shown and described, may be made without departing from the spirit or scope of the invention as set forth in the appended claims.

What I claim is:

1. An article of repose for supporting the body of a person, comprising in combination: a support, a seat pivotally connected with said support, a first extension rigid with said seat, a back-rest swingably mounted on said support at a point spaced from said pivotal connection of said seat with the support, said first extension projecting backwardly beyond the pivotal connection between said back-rest and said support, a second extension rigid with said back-rest and extending beyond the pivotal connection of the latter with the support, and a connecting link pivoted at one of its end portions to said first extension at a point spaced from the pivotal connection between said seat and the support and at its other end portion to said second extension at a point spaced from the pivotal connection between said back-rest and the support.

2. In an article of repose for supporting the

body of a person as claimed in claim 1, said first extension being offset to the plane of the seat, and said second extension being offset to the plane of the back-rest.

3. An article of repose for supporting the body of a person, comprising: a support including longitudinal rails, a back-supporting member pivoted to said support, a seat-section including a stationary seat-portion and a rockable seat-portion, said stationary seat-portion being rigid with said support, said rockable seat-portion being pivoted to said support at a point spaced from the pivotal connection between the back-supporting member and the support, a leg-supporting member, said leg-supporting member being connected with said rockable seat-portion, a first extension rigid with said rockable seat-portion, a second extension rigid with said back-supporting member, said first extension projecting backwardly beyond the pivotal connection between said back-supporting member and said support, said second extension projecting downwardly beyond the pivotal connection between said back-supporting member and said support when said back-supporting member is in upright position, a connecting link, one end portion of said connecting link being in pivotal connection with said first extension, the other end portion of said connecting link being in pivotal connection with said second extension at a point spaced from the pivotal connection between said back-supporting member and the support, and means associated with said connecting link for releasing the connection between said extensions whereby said back-supporting member, said seat-section and said leg-supporting member may be brought into alignment with each other so as to form a bed-bottom resting on said longitudinal rails.
4. In an article of repose as claimed in claim 3, the free end of the leg-supporting member being shiftably engaged with said rails when the bed-bottom is formed, and a controlling link pivoted at one of its end portions to said support, the other end portion of said controlling link being in pivotal and slidable connection with said leg-supporting member.

ANTON LORENZ.
